Primary Examiner—Charles A. Rademaker(74) *Attorney, Agent, or Firm*—Merchant & Gould P.C.**CLAIM**

The ornamental design for the front face of a telecommunications module, as shown and described.

DESCRIPTION

FIG. 1 is a front, perspective view of a front face of a telecommunications module showing my new design;

FIG. 2 is a front elevation view thereof;

FIG. 3 is a top plan view thereof;

FIG. 4 is a bottom plan view thereof;

FIG. 5 is a right end elevation view thereof; and,

FIG. 6 is a left end elevation view thereof.

The broken line showing of environment in the figure drawings is for illustrative purposes only and forms no part of the claimed design.
